CLAIM

The ornamental design for a latch assembly, as shown and described.

DESCRIPTION

FIG. 1 is a perspective view of the latch assembly of the present invention, including the receiver element and the guide element.

FIG. 2 is a top plan view of the guide element of the latch assembly shown in FIG. 1. The bottom plan view is a mirror image of FIG. 2.

FIG. 3 is an upper end view of the guide element shown in FIG. 2.

FIG. 4 is a lower end view of the guide element shown in FIG. 2.

FIG. 5 is a left side view of plan view of guide element shown in FIG. 2.

FIG. 6 is a right side view of the guide element shown in FIG. 2.

FIG. 7 is a top plan view of the receiver element of the latch assembly shown in FIG. 1. The bottom plan view is a mirror image of FIG. 7.

FIG. 8 is an upper end view of the receiver element shown in FIG. 7.

FIG. 9 is a lower end view of the receiver element shown in FIG. 7.

FIG. 10 is a left side view of the receiver element shown in FIG. 7. The right side plan view is identical.

FIG. 11 is a front elevational view of the latch assembly of the present invention, in an installed configuration on the gate of a fence.

FIG. 12 is a top plan view of the latch assembly shown in FIG. 11.

FIG. 13 is a left side view of the latch assembly shown in FIG. 11; and,

FIG. 14 is a right side view of latch assembly shown in FIG. 11.

The portions of the Figures shown in phantom lines are not part of the claimed design but are provided for illustration only.
